COMPASS

Fred De Cesaris, Johnston, R. I.

Application December 10, 1952, Serial No. 325,183

1 Claim. (Cl. 33—27)

This invention relates to a compass and more particularly to that part of the compass leg which holds a lead pencil, crayon, chalk or other marking medium.

One of the objects of the present invention is to provide a holder on a compass leg which will accommodate lead pencils, crayons, chalk and the like, having widely varying diameters and shapes.

Another object of the present invention is to provide a sturdy, neat, inexpensive, foolproof, positive acting holder for a compass.

The invention contemplates a construction of the pencil holding device involving a simply constructed hinge having one part of the hinge secured to or forming an integral part of the compass leg and a cam arrangement operably connecting the front part of the hinge to clamp or squeeze the pencil, chalk, crayon or other marking medium, in position with relation to the other leg of the compass.

Other objects of the present invention will be pointed out in part and become apparent in part in the following specification and claim.

Referring to the drawings in which similar characters of reference indicate corresponding parts in all the figures:

Figure 1 is a side elevational view of a compass embodying the new and novel pencil holder.

Figure 2 is a sectional view taken along line 2—2 of Figure 1.

Figure 3 is a side elevational view of a modified form of cam operating the hinge of the new pencil holder.

Figure 4 is an end view taken along line 4—4 of Figure 3.

Figure 5 is a perspective view of still another modified form of cam control of the hinge forming in part the new, novel and useful pencil holder.

Figure 6 is a side elevational view of another modified form of cam controlling the hinge of the new pencil holder.

Figure 7 is a sectional view taken along line 7—7 of Figure 6.

Figure 8 is a plan view of a detail part embodied in the form shown in Figure 6.

Figure 9 is a rear elevational view of the holder shown in Figure 1.

Referring to Figures 1 and 2 wherein is illustrated a compass 9 comprising a pair of legs 10, 11 pivotally connected by a pintle 12 at their upper ends. A handle 13 is connected with a short plate 14 disposed between the upper ends of the legs and associated with a mechanism for holding the handle on the central line between the legs in all possible positions of the legs. More particularly, a ball 15 is slidably mounted through crossed slots 16 and 17 formed in short plate 14 and leg 11 respectively, and through a slot in leg 10. This type of construction is generally known and for this reason the description thereof will not be amplified in this specification.

An arcuate bar 19 projects from leg 10, and extends past the other leg 11. This arcuate bar is calibrated with

2

a scale 20 adapted to show the angle to which the compass is opened. A finger 21 projects from leg 11 and indicates upon the scale 20.

A feature of this invention is a novel construction for holding a pencil 22 adjustably mounted on one of the legs of the compass. The holder comprises a segmental member or plate 23 having a semi-cylindrical body portion provided with two ears 24, 24A. One side of the segment or plate 23 is provided with an outwardly projecting ninety degree flange having a tapered or cam edge 25 and a flat face 26. A second segmental member or plate 27 having a semi-cylindrical body portion is provided with two slots 7 and 8 adapted to receive ears 24, 24A and be pivotally mounted thereby. One side of the segment or plate 27 is provided with an outwardly projecting ninety degree flange having a tapered or cam edge 28 and a flat face 29. Cam edges 25 and 28 terminate in stops 30, 31 and 32, 33 respectively. A cam follower or clamping plate 34 having opposite edges bent at ninety degrees forming a track to contact cam edges 25 and 28 is slidably mounted on faces 26, 29 which are coplanar.

Segmental or plate member 23 is either formed as an integral part of leg 10 or it is fixed to leg 10 as by soldering, brazing or welding, as shown in Figure 2.

Cam edges 25 and 28 as seen in Figure 1 taper upward. When a pencil of any shape, or crayon, chalk or the like, is inserted between segmental members or plates having semi-cylindrical body portions 23 and 27 it will pivot those members about each other. Cam follower 34 will force cam edges 25 and 28 together causing segmental members or semi-cylindrical body portions 23, 27 to grip the pencil, crayon or the like. Thus an easily operated, inexpensively made, foolproof, positive acting holder is provided on the leg of a compass. The pencil or chalk can be gripped with a force easily felt and easily determined by the user manipulating cam follower 34, saving breakage of the marking medium. The taper of cam edges 25 and 28 can be great or small and the corresponding width of cam follower 34 provided to permit segmental members 23 and 27 to accommodate very thick and very thin diameters of marking material in a range not now possible.

Figures 3 and 4 show segmental members or plates having semi-cylindrical body portions 23 and 27, cam edge 25A, faces 26, 29 and cam follower 34A which takes the form of lever pivotally mounted at 35 in face 29 and having a contact disk 36 engaging cam edge 25A. Leg 10 is fixed to segmental member or plate 27 or it forms an integral part thereof.

Figure 5 shows a modified form of cam edge 25B which permits lever 34A to control the opening and closing of the hinge comprising segmental members 23 and 27 because cam 25B is always under control of contact disk 36.

Figures 6, 7 and 8 show still another modified form of hinge control. Segmental members 23 and 27 are pivotally connected as in the previous figures through ears 24, 24A in segmental member 23 and slots 7, 8 in segmental member 27 which is united with leg 10. Faces 26, 29 and a lever 34B are provided with the modification of two pins 40, 41 riveted in faces 26, 29 respectively. Lever 34B is integrally formed with a disk 44. Two cam slots 42, 43 are provided in disk 44 which engage pins 40, 41 respectively. The edges of cam slots 42, 43 are the cams. Pins 40, 41 are the cam followers. Slot 43 is concentric with the center of the disk 44. Slot 42 is eccentric with respect to the center of disk 44. It becomes obvious to those skilled in the art, that as slot 43 rides around pin 41, slot 42 will move pin 40 toward and away from the center of disk 44. Hence face 26 and segmental member 23 will be caused to move in relation to segmental member 27 to increase or decrease the area between segmental members 23 and 27. A cap 45 to cover disk 44 and

present an aesthetically pleasing appearance is provided with two ears 46 and 47 which fit into a recess 48 in the edge of disk 44 and a slot 50 in disk 44 respectively and are bent to embrace faces 26, 29 and thereby secure cap 45 and cam follower 34B including disk 44 and faces 26, 29 together as a pivotal working unit.

Having shown and described preferred embodiments of the present invention, by way of example, it should be realized that structural changes could be made and other examples given without departing from either the spirit or scope of this invention.

What I claim is:

In a drafting compass having two separate legs pivotally connected, a pencil holder comprising two similar oppositely placed plates having semi-cylindrical body portions, one edge of one plate having ears formed thereon, one edge of the opposite plate having slots pivotally engaging said ears, opposite edges of both plates having

5 outwardly projecting flanges with tapered edges and co-planar flat faces, a wedge shaped clamping plate having inwardly projecting edges forming a track which slidily engages said tapered edges, said clamping plate lying parallel to said flat faces, one only of said oppositely placed plates being secured to one of said two separate legs, said clamping plate effecting closure of said two similar oppositely placed plates to grip the pencil therebetween.
